US0D1023347S

(12) **United States Design Patent** (10) **Patent No.:** **US D1,023,347 S**
(45) **Date of Patent:** **** Apr. 16, 2024**

(54) **CONNECTOR**

(71) Applicant: **Sur-Loc Holdings, LLC**, Kearneysville, WV (US)

(72) Inventors: **Mark Cerasi**, Kearneysville, WV (US); **Andrew Sneeringer**, Debary, FL (US)

(73) Assignee: **Sur-Loc Holdings, LLC**, Kearneysville, WV (US)

(**) Term: **15 Years**

(21) Appl. No.: **29/913,438**

(22) Filed: **Oct. 2, 2023**

Related U.S. Application Data

(60) Division of application No. 29/806,111, filed on Sep. 1, 2021, now Pat. No. Des. 1,005,094, which is a continuation of application No. 16/402,366, filed on May 3, 2019, now Pat. No. 11,286,678.

(57) **CLAIM**

The ornamental design for a connector, as shown and described.

DESCRIPTION

FIG. 1 is a top perspective view of a connector.

FIG. 2 is a front view of FIG. 1.

FIG. 3 is a back view of FIG. 1.

FIG. 4 is a right view of FIG. 1.

FIG. 5 is a left view of FIG. 1.

FIG. 6 is a top view of FIG. 1.

FIG. 7 is a bottom view of FIG. 1.

FIG. 8 is a bottom perspective view of FIG. 1, and,

FIG. 9 is an environmental front view of FIG. 1.

The broken lines rendered in FIG. 9 illustrates the environment of the claimed design and forms no part thereof.

1 Claim, 3 Drawing Sheets
